UNITED STATES PATENT OFFICE.

JOHN RAPHAEL ROGERS, OF BROOKLYN, NEW YORK, ASSIGNOR TO MERGENTHALER LINOTYPE COMPANY, A CORPORATION OF NEW YORK.

TYPGRAPHICAL MACHINE.

1,073,170.

Specification of Letters Patent. Patented Sept. 16, 1913.

Application filed November 9, 1911. Serial No. 659,283.

To all whom it may concern:

Be it known that I, JOHN RAPHAEL ROGERS, a citizen of the United States, and a resident of Brooklyn, county of Kings, and State of New York, have invented a new and useful Improvement in Typographical Machines, of which the following is a specification.

My invention relates to typographical machines, and more particularly to that class thereof known to the public under the name "Linotype", and as represented for instance in U. S. Letters Patent to O. Mergenthaler, No. 436,532. In these machines, circulating matrices stored in a magazine are released by finger keys in the required order and composed in line, and the line is transferred to the face of a slotted mold, which is then filled with molten metal to produce a slug or linotype on which type characters are formed by the matrices, the matrices being thereafter returned through a distributing mechanism to the magazine channels from which they were discharged.

The object of my invention is to provide a machine of this general class adapted to carry more than one font of matrices so that type faces differing in size or in style may be produced at will, and so that each line may be composed of matrices from one or more magazines, and their distribution be carried on continuously without reference to the character of the matrices therein. To this end, I employ a plurality of magazines arranged to deliver matrices through intermediate means to a single assembler in which the line is formed, and I arrange the magazines in parallel or substantially parallel positions, with the escapement devices for releasing the individual matrices on their inner or proximate faces, that is to say, in the space between the magazines; and for the purpose of operating the escapements of one magazine or the other at will, I employ a single series of reeds connected with the keyboard and mounted in a movable guide, so that they may be adjusted to act upon one series of escapements or the other at will. Assembling mechanism of the general type last described is presented in my previous Letters Patent No. 961,799, dated June 21, 1910, and consequently constitutes no part of the present invention. In the said Let-

ters Patent, a distributor rail or bar is shown in operative relation to each of the magazines, and the mode of distribution contemplates that all of the matrices are transferred to one of the rails which delivers to the proximate magazine the matrices belonging therein, while the matrices for the second magazine travel the entire length of the first bar, and are then transferred to the second rail or bar, along which they travel in a reverse direction, and by which they are delivered into their appropriate channels in the second magazine. In the present instance, and as disclosed in the drawings, I similarly employ two magazines, which are arranged in approximate parallelism, but wherein the channel mouths or throats of both magazines are brought into a common bank and are alternately disposed, that is to say, each mouth or throat of one magazine is arranged at the side of and in proximity to the corresponding mouth or throat of the other magazine, so that the first, third, fifth, etc., mouths or throats in the bank belong to one of the magazines, while the second, fourth, sixth, etc., mouths or throats belong to the other magazine. This arrangement of the throats or entrances in one bank permits the employment in connection therewith of a single distributor bar or rail which delivers the matrices to both magazines, instead of having two distributor rails for that purpose, as in my previous patent and as above described herein. To this end, the longitudinally grooved distributor rail, and the toothed notches of the matrices engaging therewith, are each formed with both channel-controlling combinations and also magazine or font-controlling combinations, whereby the matrices of different fonts are freed from their channel-combinations at the same point and from their magazine-combinations at a different point. In the specific form illustrated, and due to the disposition of the corresponding channel entrances of the different magazines in pairs, side by side and in immediate proximity to each other, the matrices of both channels are freed from the rail, so far as the channel-combination is concerned, over the first entrance of the pair. Simultaneously the matrices belonging to this first channel are freed from the font or magazine-combina-

tion and are therefore permitted to drop therein. While the matrices belonging to the second channel are also freed from their channel-combination at this point, they are not released from the rail, but are still sustained by their font or magazine-combination, until in the advance of the matrices along the rail they reach the second entrance of the pair, at which time they are also freed from their font or magazine-combination, and are thereby enabled to drop into the corresponding channel of the other magazine. In the present instance, both the channel-combinations and the font or magazine-combinations are formed upon the grooved rail and within the notches of the matrices which engage therewith, without recourse to supplementary or outside means for sustaining the matrices after they are freed from their channel-combinations, such as are known in the art.

My invention is capable of application in various forms, and in the accompanying drawings I have disclosed one preferred embodiment by way of example. Generally speaking, I do not desire to limit myself to any particular form or embodiment except in so far as such limitations are specified in the claims.

Referring to the drawings: Figure 1 is a front view of a portion of a linotype machine having my invention applied thereto; Fig. 2 is a vertical transverse section taken substantially on the line 2—2 in Figs. 1 and 4; Fig. 3 is a similar view taken substantially on the line 3—3 in Fig. 4; Fig. 4 is a plan view of the bank of channel entrances, as indicated by the line 4—4 in Fig. 3; Fig. 5 is a partial view on an enlarged scale of the distributor rail, indicating the manner in which the matrices are freed therefrom; Fig. 6 is a transverse sectional view of the distributor rail, illustrating the release of a matrix belonging to the upper magazine; Fig. 7 is a similar view illustrating the release of a matrix belonging to the lower magazine; Fig. 8 is a partial perspective of two matrices belonging respectively to corresponding channels in the two magazines; and Fig. 9 is a vertical sectional view taken substantially on the line 9—9 in Fig. 1.

Referring to the drawings, and more particularly to Figs. 1 and 9 thereof, B and B¹ are two inclined magazines suitably mounted in the main frame A, the said magazines being disposed one over the other and each adapted to carry a font or set of matrices C or C¹. The upper magazine B is of the usual Mergenthaler construction, except that its throats or entrances O (see Figs. 2 and 3) are continued in straight lines to their upper extremities; and the lower magazine B¹ is similarly of the usual construction, except that its throats or entrances O¹ are vertically curved so as to bring them to the same level

as the throats O of the magazine B. The throats or entrances of both magazines are alternately disposed in a common bank (see Fig. 4), so that the throat or entrance O of each channel of one magazine lies at the side 70 of the throat or entrance O¹ of the corresponding channel of the other magazine, that is to say, the first, third, fifth, etc., throats O in this common bank lead to the upper magazine B, while the second, fourth, sixth, etc., throats O¹ lead to the lower magazine B¹. This alternation of the channel throats or entrances necessarily results in a magazine of greater width than is ordinarily employed, as is clearly indicated in Fig. 1 of 80 the drawings.

The discharge of the matrices from the magazines, one at a time in the order in which they are required, may be effected by escapement devices of any suitable form connected with the keyboard mechanism, as well understood in the art. I prefer, however, the construction shown in Fig. 9, in which the upper magazine is provided on the underside with the escapements D, while the lower magazine is provided on its upper side with the corresponding escapements D¹. The escapement levers of the two series have their lower ends terminated side by side and in position to be actuated by vertically sliding reeds E equal in number to the escapements in one magazine. The lower ends of the reeds have a permanent connection with the keyboard, but the upper ends are mounted in a horizontally movable guide F, connected to an angular hand lever G provided in the frame, so that by moving the lever, the guide F may be shifted forward and backward and the reeds caused to actuate the escapements of the upper or lower magazines as required. The matrices delivered from the magazines descend through two vertically channeled plates H, H¹, and below the respective plates are arranged parallel inclined plates I and I¹, by which the matrices are directed downward to the upper end of a forked guide J, through which they descend successively to the usual assembler elevator K, in which they are assembled and advanced under the influence of the star wheel or pusher L. This arrangement admits of the matrices from either or both of the magazines being assembled at will in a common line in the assembler, from which the matrix line will be transferred to the casting mechanism, and thence to the second elevator M, by which it is lifted to the distributing mechanism above the magazines. As the casting and transferring mechanism can all be of ordinary construction and are foreign to my invention, it is unnecessary to describe them herein. After the matrices have been lifted by the second elevator M, they are transferred to the distributor screws R, R, which operate 130

in the customary manner to pass them along the distributor rail or bar N, from which they are restored to their respective magazines. The construction and arrangement 5 of the releasing combinations on the rail and in the notches of the matrices will now be described.

The standard rail has ordinarily seven ribs on each side, and the standard matrices 10 have coöperating teeth in seven positions. To increase the number of combinations sufficiently, an additional rib is added to each side of the distributor rail, and the teeth of the matrices are arranged in eight positions 15 instead of seven. Referring particularly to Figs. 5-8, it will be seen that the distributor rail N is formed with eight ribs, and that the lower seven are varied and permuted to constitute the letter or channel- 20 combinations, whereby the matrices belonging to the corresponding channels in the different magazines are freed from the rail N at the same point. This does not imply that the matrices drop from the bar at this point, 25 for the reason that they are also provided with font or magazine-combinations, which latter are controlled by the upper rib on the rail N. The matrices C and C¹, which belong 30 respectively to the magazines B and B¹, are similarly formed as to their lower seven teeth with letter or channel-combinations. However, the matrix C is formed with blanks Y in the upper or eighth position, so 35 that it drops from the rail at the same time that it is freed from its letter or channel-combination. The matrix C¹ is formed as to its lower seven teeth with a letter or channel-combination in the same manner as the matrix C, but in its upper or eighth position the matrix C¹ is formed with teeth 40 X which engage with the upper rib of the rail N.

The operation of the parts will now be apparent. As previously described, the matrices pass along the rail in the direction indicated by the arrow in Fig. 5 until a matrix C arrives at the point indicated by dotted lines, where its letter or channel-combination is freed from the bar N. At this 45 point, the upper rib on the rail N projects, as indicated at Y¹, but it is ineffective with reference to the matrix C, due to the blank Y thereon, and consequently the matrix C is released from the rail and drops therefrom, as indicated in Fig. 6. When a corresponding matrix C¹ arrives at the same 50 point, it is similarly freed from the rail, so far as its letter or channel-combination is concerned, but is not released due to the engagement of its tooth X with the projection Y¹. Consequently, it travels along the rail until it reaches the point X¹ where the upper rib is cut away. There is nothing now 55 to support the matrix C¹, as it was formerly freed from its letter or channel-combina-

tion, and therefore it drops from the rail at this point, as indicated in Fig. 7. Due to this construction of the rail and of the matrix notches, and also to the alternate disposition of the channel mouths or entrances O and O¹, it follows that of a corresponding pair of matrices C and C¹, the matrix C will be delivered through the entrance O into the magazine B, and the matrix C¹ into the adjoining entrance O¹ of 70 the magazine B¹. In this manner I am enabled to employ a single distributor rail to deliver matrices of different fonts into two magazines simultaneously, and this simply by altering the formation of the longitudinal grooves or ribs on the rail and of the teeth in the notches of the matrices, and without recourse to outside or auxiliary sustaining means, such as are known in the art. 80 As previously stated, my invention has been 85 illustrated only in preferred form and by way of example, and obviously many changes and variations may be made therein without departing from its spirit.

Having thus described my invention, its 90 construction and mode of operation, what I claim and desire to secure by Letters Patent of the United States is as follows:

1. In a typographical machine, a plurality of magazines containing matrices, 95 each matrix having a single toothed notch, the throats or entrances of the several magazines being brought into a common bank and alternately disposed, in combination with a distributing mechanism having a 100 grooved rail to engage the matrix teeth and arranged in operative relation to the said bank, the said teeth and grooves being permuted to free the matrices from the rail at the same point according to letter and at 105 different points according to font.

2. In a typographical machine, a plurality of magazines containing matrices, 110 each having a single distributing notch, the throats or entrances of the several magazines being brought into a common bank and alternately disposed, in combination with a distributing mechanism having a rail arranged in operative relation to the said bank, and the said rail and the matrix- 115 notches being each formed with channel-combinations and also with magazine-combinations; whereby the matrices of the different magazines are freed from their channel-combinations at the same point and 120 from their magazine-combinations at different points, so as to enter respectively the alternately disposed throats or entrances.

3. In a typographical machine, two magazines containing matrices, each having a 125 single distributing notch, the throats or entrances of corresponding channels in the two magazines being alternately disposed in pairs in a common bank, in combination with a distributing mechanism having a rail 130

arranged in operative relation to the said bank, and the said rail and matrix-notches being each formed with channel-combinations and also with magazine-combinations; 5 whereby the matrices are freed from their channel-combinations at the same point and from their magazine-combinations at different points, so that matrices of one magazine will enter the first entrance of each pair

and matrices of the other magazine will 10 enter the second entrance of the pair.

In testimony whereof I hereunto set my hand this sixth day of November, 1911, in the presence of two attesting witnesses.

JOHN RAPHAEL ROGERS.
